SKEE BALL GAME TABLE

John W. Jamison, Inglewood, Calif., assignor to Eldon Industries, Inc., Hawthorne, Calif., a corporation of California

Filed Nov. 12, 1963, Ser. No. 77,339

Term of patent 14 years

(Cl. D34—5)

FIG. 2.

FIG. 3.

FIG. 4.

FIG. 5.

FIG. 6.

FIGURE 1 is an isometric view of a skee ball game table showing my new design;
 FIGURE 2 is a right side elevation thereof;
 FIGURE 3 is a left side elevation thereof;
 FIGURE 4 is a top plan view thereof;
 FIGURE 5 is a front elevation thereof; and
 FIGURE 6 is a rear elevation thereof.

I claim:
 The ornamental design for a skee ball game table, substantially as shown.
